UNITED STATES PATENT OFFICE.

THOMAS W. SCOTT, OF BALTIMORE, MARYLAND, ASSIGNOR TO THE AMERICAN TRAIN CONTROL COMPANY, OF BALTIMORE, MARYLAND, A CORPORATION OF MARYLAND.

ELECTROPNEUMATIC VALVE FOR AIR-BRAKES.

1,230,083.

Specification of Letters Patent. Patented June 12, 1917.

Application filed January 31, 1914. Serial No. 815,626.

To all whom it may concern:

Be it known that I, THOMAS W. SCOTT, a citizen of the United States, residing at Baltimore, in the State of Maryland, have 5 invented certain new and useful Improvements in Electropneumatic Valves for Air-Brakes, of which the following is a specification.

This invention relates to an electro-pneumatic valve for air-brakes to be used in an 10 electric train-controlling mechanism on rail-ways.

The present invention is applicable for 15 use in a safety system similar to that set forth in U. S. Patent 1,010,371 and is particularly an improvement on the device shown in U. S. patent granted December 31st, 1912 to Frank T. Jones.

The object of the present invention is to 20 provide an improved electro-pneumatic valve mechanism which when operated automatically to actuate the air-brakes will simply effect such reduction in the train line or train-pipe pressure to cause an application 25 of the brakes, without, however, producing a so-called emergency application of said brakes.

Heretofore in safety-train control devices, 30 where an air-brake valve has been actuated to automatically stop the train a considerable quantity of train line air has been allowed to escape thereby producing an emergency application, whereas it is desirable that only so much air be vented as will 35 cause a gradual stopping of the train, and another object of the present invention is to provide a safety control valve that will automatically close when the train line pressure is reduced, sufficiently to apply the 40 brakes and will automatically open again in case the train line pressure is restored to a point where the brakes would tend to release. **

With these and other objects in view, the 45 invention is illustrated in the accompanying drawing, wherein—

Figure 1, shows in a diagrammatic way, a track rail, a ramp rail and the devices and circuits on the vehicle, including the im- 50 proved valve device.

Fig. 2, illustrates the improved electro-

pneumatic valve mechanism in vertical section, and

Fig. 3, shows a front elevation of the case containing the improved valve mechanism. 55

Referring to the drawings, the numeral, 3, designates a box or case which may be located at any convenient place on the locomotive or motor and which has a hinged cover, 4. 60

A pipe, 5, enters the case, and said pipe is in continuous communication with the train line of the air-brake apparatus.

Another pipe, 6, enters the casing and communicates with the main reservoir or 65 is constantly supplied with air-pressure from the main reservoir of the air-brake apparatus, and said pipe, 6, is secured by a coupling, 7, to a nipple, 8, which is attached to a shell, 9. The nipple has a passage, 10, 70 therein and a strainer, 11, is interposed in said passage to strain the air entering from the pipe, 6.

The shell, 9, is clamped by a yoke, 12, against a block, 13, that is carried by one 75 of the walls of the inclosing box or case and said shell has a chamber, 14, and a lateral passage, 15, from said chamber which extends beneath the passage, 10, of the nipple. A port, 16, extends through the wall of the 80 shell between the nipple-passage, 10, and the lateral passage, 15, so that under certain conditions, presently to be explained, communication between the nipple-passage, 10, and the lateral passage, 15, and chamber, 14, 85 may be established.

Below the lateral passage, 15, the shell has a wall through which a port, 17, extends which latter port has position in alignment with the port, 16, at the upper side of the 90 lateral passage, so that a valve stem, 18, may extend through port, 16, across the lateral passage, 15, and also extend loosely through port, 17. The upper side of port, 16, has a seat, and a head, 19, on the stem, 18, serves 95 to engage the seat and thereby close or shut off communication between the main reservoir and the lateral passage, 15, under certain conditions, presently to be explained.

The interior of the nipple passage contains a perforated disk or washer, 20, which seats against a shoulder in the passage, and 100

a spring, 21, extends from said washer and presses on the valve stem, 18, to aid in seating the head, 19, on the port, 16.

Suitable pipe connections, 22, lead from 5 the chamber, 14, in the block, 13, and said pipe connects and communicates with one end of a cylinder, 23, in which a floating piston, 24, is confined. One side of the floating piston, 24, is exposed to any air-pressure 10 that may be present in the chamber, 14, while the other side of said piston has a tapered valve-end, 25, which under certain conditions will seat on a port, 26. The wall of the cylinder, 23, is provided with one or 15 more escape ports, 27, which are located above the port, 26, and between the latter and the piston, 24; and said escape ports serve to vent the train-line from pipe, 5, through a valve which will now be explained.

Pipe, 5, which always communicates with the train-line, enters a chamber, 28, of a valve casing, 29, in which there is a partition, 30, having a port, 31. On the other 25 side of the partition, the casing has another chamber, 32, with which the lower end, 33, of the cylinder, 23, is in continuous communication.

A valve, 34, seats on the partition around 30 the port, 31, and is yieldingly held against its seat and over said port by means of a spring, 35, which encircles the valve stem, 36.

In practice it is designed that the spring, 35, shall exert a pressure on the valve, 34, 35 that will cause said valve to seat over port, 31, when the train line pressure shall have been reduced sufficiently to cause an application of the brakes, and before a sufficient reduction in train line pressure is made to 10 cause an emergency application of the brakes.

From the foregoing explanation it will be seen that the floating piston, 24, in cylinder, 23, has one side subject to main reservoir 15 pressure and its opposite side subject to train line pressure, so that when the pressures on opposite sides of the floating piston are equalized, the latter will seat on port, 26, because the piston has a greater area exposed 20 to main reservoir pressure, and cut off the escape of air pressure from chamber, 32, through vent-ports, 27.

Under normal running conditions the floating piston will be seated on port, 26, while 55 the pressure below the piston, in chamber 32, will equal substantially the excess of train pipe pressure over the adjustment of spring 35. The spring, 35, has a pressure resistance somewhat less than the normal running 60 pressure in the train line and main reservoir, therefore when the train line pressure builds up to a point where it will overcome the pressure of spring, 35, such pressure will feed under valve, 34, and into

chamber, 32, until the two chambers, 28, 65 and, 32, are uniformly charged.

It is therefore to be understood that as long as the normal running pressure is maintained on the reservoir side of the floating piston a venting of the train line 70 through valve, 34, will be prevented because floating piston will seat on port, 26, and prevent the escape of train line pressure through vent ports, 27.

The means employed to control the reservoir pressure will now be explained.

Below the port, 17, and lateral passage, 15, the shell, 9, has a screw-threaded socket, 37, into which a threaded stem, 38, screws and is pendants sustained thereby, and the wall 80 of the shell at the lower end of said port, 17, has a concave seat, 39, for a purpose presently to be explained. Between the seat, 39, and stem, 38, is an annular chamber, 40, and a relief port, 41, extends from said 85 chamber through the wall of the shell to the atmosphere.

The stem, 38, in reality is the core of an electro-magnet, 42, and has a central passage, 43, in which a stem, 44, of an armature, 45, extends. The upper end 46, of the armature-stem is beveled or shaped to form a valve to fit the concave seat, 39, so that when the electro-magnet is energized, and armature 45, is held up the end of armature-stem, 44, will engage and hold valve-stem, 18, up, thereby raising head, 19, to allow reservoir air to pass to chamber, 15. At this same time the armature stem will close the lower end of port, 17, and prevent the 100 escape of air from passage, 15, to chamber, 40, and relief port 41.

It will therefore be understood that as long as electro-magnet 42 is energized, the upper side of floating piston, 24, will be subject to reservoir air-pressure, and the escape of that pressure cannot take place because armature-stem, 44, will remain seated at the lower end of port 17.

The electro-magnet, 42, is inclosed in a 110 cylindrical casing, 47, and the armature, 45, contained in a cap, 48, at the lower end of the casing. This cap has a depending central stem, 49, with a central passage therein and a spindle, 50, is loosely confined 115 in said passage so as to be moved vertically, and during such movement engage the armature and raise the latter when resetting is necessary. The lower end of the spindle, 50, carries a resetting yoke head, 51, also 120 for a purpose presently to be explained.

By referring to Fig. 2, of the drawing it will be noted that a pipe, 52, branches from the train-line pressure-pipe, 5, and that a valve, 53, is located in said branch, and it will 125 also be noted that a lever, 54, is mounted on the stem of said valve, 53, and extends across to the yoke-head, 51, with which it is

connected. The valve, 53, in this branch is normally closed but is momentarily turned to the open position by means of an operating handle, 77, to rock the lever, 54, and raise the yoke-head, 51, to reset the armature, 45, as will presently be more fully explained.

In practice the box or case, 3, containing the improved valve mechanism is located in the engine or motor and the electro-magnet, 42, has two binding posts, 55, and, 56. A current supply, such as a battery, 57, is provided on the vehicle as is also a contact shoe, 58, which rides over or engages short ramp rails, 59, that are located at spaced-apart intervals along the roadway. A switch, 60, is provided and so arranged with respect to the contact shoe as to close a connection between two contact points, 61, and, 62, when the vehicle is traveling between ramp rails and when the shoe engages a ramp rail said switch will be actuated to open or break the normal connection between the contacts, 61, and, 62.

A wire, 63, connects electro-magnet binding-post, 56, with contact-point, 62, and a wire, 64, connects contact point, 61, with one side of the current-supply, 57.

In the present instance a wire, 65, connects binding post, 55, of the electro-magnet with the axle, 66, and another wire, 67, connects the axle with the other side of the current-supply, 57.

It will therefore be seen that when the contact shoe, 58, is in the normal running position, as during the travel of the vehicle between ramp rails, a circuit from battery, 57, through electro-magnet, 42, will be maintained and said magnet thereby maintained in an energized condition.

While the shoe, 58, remains in engagement with a ramp rail, 59, however the switch, 60, will open the connection between contacts, 61, and, 62, and thereby interrupt the normal vehicle circuit from battery, 57, through electro-magnet, 42, but during such engagement of the shoe with a ramp rail, provided the road ahead is clear, the shoe will pick up a local current from the ramp rail as follows:

From battery, 68, by wire, 69, to and through an armature, 70, that is held by an electro-magnet, 71, which latter is energized by a local current, not illustrated; then by wire, 72, to ramp rail, 59, and shoe, 58; by wires, 73, and, 63, to binding post, 56, of vehicle magnet, 42; then from post, 55, and wire, 65, to axle, 66, wheel, 74, and track-rail, 75, and finally by wire, 76, back to local battery, 68.

It is therefore to be understood that during clear track conditions the electro-magnet, 42, on the vehicle will be energized by vehicle current from battery, 57, while the

vehicle is traveling between ramp rails and by current from a local battery, 68, while the shoe, 58, is traveling over a ramp rail. When however, the track ahead is occupied, track magnet, 71, will become de-energized and drop armature, 70, so that current from local-battery, 68, cannot pass to ramp rail, 59. Therefore when shoe, 58, rises up on ramp rail, 59, which latter has become disconnected from battery, 68, a substitute current cannot be supplied to the magnet, 42, on the vehicle and the latter will become de-energized and cause an application of the brakes, as will now be explained.

It has hereinbefore been explained that during normal running conditions reservoir pressure is present in lateral passage, 15, chamber, 14, and pipe connections, 22, so as to exert a force on the upper side of floating piston, 24. During this period as also explained, armature, 45, and stem, 44, will be elevated to prevent the escape of reservoir pressure through port, 17, chamber, 40, and relief-port, 41.

It is also to be understood that during normal running conditions the under side of floating piston, 24, will be subject to train line pressure which may vary according to the various manipulations of the engineer's valve in the usual operations of producing graduations and service applications of the brakes.

It should be understood that reductions in train line pressure will in no way affect or produce an operation of the controlling-valve mechanism in this case.

When a block or section in advance of a moving train is occupied, the ramp rail for that section will be disconnected from its local current supply so that when the contact shoe, 58, rides up onto such ramp rail it will move switch, 60, and interrupt the normal vehicle circuit between vehicle battery, 57, and electro-magnet, 42, and having no substitute current from the ramp rail, the said electro-magnet will become de-energized and allow armature, 45, and armature-stem, 44, to drop. When armature-stem, 44, drops its upper beveled end, 46, moves away from and uncovers the lower end of port, 17. During this downward movement of the armature-stem, valve-stem 18, will also move downward until head, 19, thereon seats on the upper end of port, 16, thereby cutting off the passage, 15 from the reservoir pipe, 6. At this time air-pressure escapes from passage, 15, and chamber, 14, around the stem, 18, which loosely fits the port, 17, and such escaping air-pressure passes through chamber, 40, and relief port, 41, to the exterior or atmosphere.

Thus it will be understood that the de-energization of electro-magnet, 42, will open

ports and allow the air pressure on the reservoir side of the floating piston to escape, and at the same time cut off the supply of reservoir pressure to that side of the floating piston. The pressure therefore on the reservoir side of the floating piston being reduced below that on the under or train-line side of the floating piston, the latter will move up in the cylinder, 23, and uncover ports, 27, so that the pressure in the chamber, 32, of valve, 29, will be vented; valve, 34, will be unseated and air-pressure from the train-line will pass through port, 31, to chamber, 32, and then into the end, 15 33, of the cylinder from which latter it will also escape through ports, 27. It will therefore be seen that when electro-magnet, 42, becomes deenergized, reservoir pressure will be shut off from the upper side of floating 20 piston, 24, and the latter will rise so as to uncover port, 26, and also vent train line air from the chamber, 32. This it will also be seen, will cause train-line pressure in chamber, 28, to open valve, 34, and thereby vent 25 the train-line and cause an application of the brakes.

If valve, 34, were omitted, the train-line pressure would continue to vent through ports, 26, and, 27, until said train-line is depleted of pressure and such a reduction of pressure in the train-line would result in an emergency application of the brakes. An emergency application of the brakes is undesirable in the absence of immediate danger, because of the liability of damage to the rolling stock by strains, jars and in many instances the shifting of the loads on the various cars of the train. To avoid these objections I have interposed the train-line 30 pressure control-valve, 34, between the floating piston and the source of train-line pressure so that the reduction of train-line pressure shall be only partial instead of a depletion. In practice the reduction in train-line pressure by means of my improved mechanism, is less than necessary to cause an emergency application, because the spring, 35, is designed to close valve, 34, against the train-line pressure after a predetermined reduction in that pressure has been made. For example, if under normal running conditions the train line and reservoir pressures equalize at seventy pounds pressure, and a ten pound reduction in 35 train-line pressure will cause a prompt application of the brakes, but not an emergency application, the spring, 35, will be designed to close the valve, 34, against a sixty pound air-pressure in the chamber, 28. By this means when a ten pound reduction in the train-line pressure has been made, the valve, 34, will close, but the brakes will have 40 been applied.

After the valve, 34, has closed with the

brakes applied, and the pressure in the 65 train-line is being restored when that train-line pressure reaches a point where it will overcome the action of spring, 35, the valve, 34, will again open until the pressure is reduced below that of the spring when said 70 valve will again close, but at no time will the reduction of train-line pressure be sufficient to produce an emergency application of the brakes.

This condition of intermittently venting 75 the train-line will maintain the brakes in an applied condition until the armature, 45, of electro-magnet, 42, is reset, but a resetting of this armature cannot take place unless the engineer brings his train to a stop, as he 80 should, or get an emergency application of the brakes.

To effect a resetting, the engineer, who cannot gain access to the mechanism in the case, 3, will grasp handle, 77, on the exterior 85 of the case which handle is mounted on the stem of valve 53. By turning this handle, 77, valve, 53, will be turned from a normally closed position to an open position in which it will vent the train-line through branch, 90 52, and an emergency application will result. At this time however, the train will have come to a full stop, or substantially a full stop. In making this turn of handle, 77, the lever, 54, will be swung upwardly so 95 that its free end will elevate the yoke-head, 51, and stem, 50. This upward movement of stem, 50, will raise armature, 45, and armature-stem, 44, which latter in turn will move valve stem, 18, to uncover port, 16, and 100 again admit reservoir pressure to chambers, 15, and, 14, thereby restoring floating piston to its normal seated position on port, 26. Having reset the armature, the normal vehicle circuit from battery, 57, to electro-magnet, 42, and back will be reestablished and the resetting handle, 77, may be returned to its normal position so as to close valve, 53, and allow the train-line pressure to build up 105 and equalize with the reservoir pressure.

Having thus described my invention what I claim and desire to secure by Letters Patent is:—

1. In an air-brake valve device for vehicles, the combination with a vehicle having 115 an air-brake system, of a connection subject to train-line pressure of the said system; a connection subject to main-reservoir pressure of said system; valve means having one side subject to reservoir pressure and another side subject to train-line pressure, said valve means holding the train-line connection closed, and means interposed between said valve means and the train-line to limit the reduction in train-line pressure and 120 prevent an emergency application of the brakes when said valve means has been opened to vent the train-line.

2. In an air-brake valve device for vehicles which latter travel on tracks, the combination with a vehicle having an air-brake system, of a train-line connection with the 5 air-brake system; a connection from the main reservoir of the said air-brake system; means for normally holding the train-line connection closed by pressure from the reservoir; valve means for controlling the reservoir pressure to the said closing means of the train line; an electro-magnet to control 10 said valve means; a circuit on the vehicle which includes the said electro-magnet; means for automatically controlling said 15 circuit and electro-magnet, and automatic means in the train-line connection to limit the reduction of train-line pressure and automatically prevent an emergency application of the brakes when the train-line 20 holding means is opened.
3. In an air-brake valve device for vehicles which latter travel on tracks, the combination with a vehicle having an air-brake system, of a cylinder on the vehicle having 25 a movable piston-head; a connection between one side of the head in said cylinder and the train-line pressure of the air-brake system; automatic means for normally retaining said head to prevent escape of air 30 from the train line, said means including an electro-magnet; a circuit including said electro-magnet to keep the latter energized and automatic means in the said connection to limit the reduction in train-line pressure and automatically prevent an emergency application of the brakes when the said head is moved to open the train line. 35
4. In an air-brake valve device for vehicles which travel on tracks; the combination with a vehicle having an air-brake system of 40 a cylinder on the vehicle having a movable piston head therein; an air-brake train line connection with the cylinder and at one side of the piston head; an air-brake reservoir connection with the cylinder and at the 45 other side of the piston head normally hold the said piston head to prevent the escape of air from the train line; means for automatically controlling the reservoir connection to the cylinder and automatic means to limit the reduction in train-line pressure and automatically prevent an emergency application of the brakes when the piston head is moved to vent the train-line. 50

In testimony whereof I affix my signature 55 in presence of two witnesses.

THOMAS W. SCOTT.
